STROKING HOLDER FOR RAZOR BLADES

Charles E. Edwards, New Britain, Conn.

Application March 5, 1934, Serial No. 714,079

8 Claims. (Cl. 30—98)

My invention relates to improvements in stroking holders for razor blades of the form that is used to hold a blade for a safety razor for stroking on a razor strop or the like and the object of my improvement is to produce a stroking holder for razor blades of the form in which the blade is provided with an elongated transverse slot that extends across the middle of the blade for substantially the length of the cutting edges of the 10 double edged blades and in which slot I find it convenient and effective to house a key of rod-like form and that cooperates with a ribbed one-piece holder proper for holding the blade during the stroking or stropping, the ribs on the holder 15 serving to provide the proper angle of contact with the strop for providing the proper edge to the blade.

In the accompanying drawing:—

Figure 1 is a side elevation of my improved 20 stroking holder for razor blades and with a razor blade held therein.

Fig. 2 is an edge view of the same.

Fig. 3 is a sectional view on an enlarged scale 25 showing the invention in use, a part of a strop being shown.

Fig. 4 is a sectional view showing the partially closed end of the rib or trough in the bottom wing of the holder for retaining the key-rod.

Fig. 5 shows a blade.

Fig. 6 shows the blank for the holder proper.

My improved stroking holder for razor blades, as shown, is adapted for use with a blade 10 of the two-edged form such as is in common use at the present time in that it is provided with a slot 11 of elongated form that extends transversely along the middle of the blade. Said slot 11 is usually incidental to other details and merely serves to merge or inter-connect a set of openings of various forms that are adapted to operate with positioning projectors on one or the other or both of the elements of the blade clamping structure, consisting of the guard and the cap. A screw-threaded handle may serve as the means for effecting the clamping pressure.

In the present instance the slot 11 is utilized substantially as a whole for operatively housing the device that serves as a key for holding the blade in place in the holder proper and the border edge elements 12 of nearest approach fit against the key-rod 13 for effecting the positive positioning of the blade 10.

The key may be said to operatively fill the slot.

The slot 11 is nearly as long as the edges 14 of the blade 10.

The holder 15 comprises two similar blade

parts 16 that are opposed to one another in face-to-face relation so as to be adapted to have the blade 10 slipped therebetween. Said parts 16 are in the form of plate-like blades of sheet metal of appreciably less width than the length of the 5 blade 10 from edge to edge, so that the blade edges 14 will be exposed for sharpening with the blade located symmetrically therein.

Such symmetrically placing of the blade is effected by means of the key 13, which is merely 10 a length of rod, and which is housed within opposed grooves 17 that are provided in the opposed plate-like parts or wings 16. The key-rod 13 fits within the grooves 17.

The wings 16 are parts of a one-piece structure 15 18 that is made of material that is grooved from end to end and doubled back upon itself.

Such doubling back is preferably done to one side of the middle of the particular length of the stock that is utilized to make the holder proper 20 so that the two wings will be of different length.

Thus, as shown, the return bend 19 provides the hinge connection for the two wings, and the latter are as a whole longer than the transverse width of the blade so that by having the blade located 25 adjacent the free ends of the wings the holder portion 20 intermediate the blade and the hinge connection will be adapted to serve as the handle for manipulating the device under conditions of use.

As shown, the lower or rear wing 16 is provided with an extension 21 of the free end portion that facilitates the insertion of the blade and the key into the operative relation.

When not in use the key is retained within the housing that is provided by the grooves 17 and to prevent accidental removal thereof the tip end portion 22 of the groove 17 of the extension 21 is partially closed so as to provide an abutment that serves as a retaining device.

The material that is shaped to provide the grooves 17 appear on the outside as ribs 23 that provide the desired angle of contact of the blade with the strop 24.

I claim as my invention:—

1. In a stroking holder for razor blades, a holder proper comprising opposed plate-like wings, said wings being provided with registering grooves, and a key of rod-like form and uniform cross section fitting within the space that is provided by said grooves, whereby means are provided for operatively holding a slotted blade positioned between said wings for stropping the blade.

2. In a stroking holder for razor blades as de-

55

scribed in claim 1, means inter-connecting said wings at one end, one of said wings having an extension at the other end that overhangs the adjacent end of the mating wing, and the material of said extension being shaped to provide an abutment for the key at the extreme end of the groove therein.

3. In a stroking holder for razor blades as described in claim 1, said holder being in the form of a single piece of sheet metal, the two wings being connected by a return bend of the material.

4. In a stroking holder for razor blades, opposed wings of plate-like form having registering grooves on the opposed faces that cooperate to provide a housing chamber and having outwardly projecting ribs on their outside faces, and a rod-like key fitting within and substantially filling said chamber.

5. In a stroking holder for razor blades for use with a blade that is provided with a relatively elongated transverse slot along the body portion, a two-winged grooved holder proper for engaging the blade interposed between the wings and a key housed in the groove operatively holding the blade positioned when so interposed, and said key being in the form of a rod of plain form and uniform cross-section.

6. In a stroking holder for razor blades, a holder proper comprising opposed wings held normally in opposed relatively elongated face-to-face relation by means of an integral return-bend and adapted to receive a razor blade between the two opposed faces, grooves in said wings adapted to register with a slot in the blade for providing a housing chamber, the said return-bend being at one end, and a key in the form of a separate loose

piece insertable in said chamber for retaining the wings and the blade in operative relation, one wing being longer than the other so as to provide an extension for facilitating the insertion of the key.

7. In a stroking holder for razor blades, a holder structure comprising a pair of opposed wings for receiving a blade therebetween, said wings being individually shaped so as to provide on the opposed inside faces registering chamber forming depressions and on the outside faces rib-like projections that extend longitudinally of the wings, said wings at one end of the structure being in the form of free end portions for permitting of relatively free and unobstructed admission of the blade, and the wings at the other end of the structure being operatively connected by means of an integral resilient return bend, the depression in one of said free end portions being obstructed by means of integral material near the tip end.

8. In a stroking holder for razor blades, a holder proper comprising opposed relatively elongated wings held normally in opposed face-to-face relation and adapted to receive a razor blade between the opposed faces, grooves in said wings adapted to register with a slot in the blade for providing a housing chamber, a key in the form of a separate loose piece insertable in said chamber for retaining the wings and the blade in operative relation, and material integral with part of the end structure of said chamber shaped to provide an abutment for obstructing accidental escape of the key from the chamber.

CHARLES E. EDWARDS.
